(57) **CLAIM**

The ornamental design for a shock mount, as shown and described.

DESCRIPTION

FIG. 1 is a front perspective view of a shock mount, showing my design.

FIG. 2 is a rear perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of an area labeled 9 in FIG. 1; and,

FIG. 10 is an enlarged view of an area labeled 10 in FIG. 2. The evenly-dashed broken lines show portions of the shock mount that form no part of the claimed design. The evenly-dashed broken lines that are immediately adjacent to shaded areas and define unshaded regions represent boundaries to the claim. The dot-dash broken lines encircling portions of the shock mount in FIGS. 1, 2, 9, and 10 indicate that portions of the shock mount are illustrated in the enlarged FIGS. 9 and 10. The dot-dash broken lines form no part of the claimed design.
